[57] **CLAIM**

The ornamental design for surgical pledgets, substantially as shown and described.

DESCRIPTION

FIG. 1 is a top plan view of a surgical pledget embodying my new design;

FIG. 2 is a bottom plan view thereof;

FIG. 3 is a side elevational view thereof, the side remote from the side illustrated being a mirror image of the side illustrated;

FIG. 4 is an end elevational view of one end thereof; and

FIG. 5 is an end elevational view of the other end thereof.
